Primary Examiner — Ricky Pham(74) *Attorney, Agent, or Firm* — Carter, DeLuca, Farrell & Schmidt, LLP**CLAIM**

The ornamental design for a rotisserie, as shown and described.

DESCRIPTION

FIG. 1 is a perspective view of a rotisserie in accordance with the present design;

FIG. 2 is a front side elevational view thereof;

FIG. 3 is a rear side elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the drawings illustrate portions of the rotisserie that form no part of the claimed design.

1 Claim, 6 Drawing Sheets---
